COMBINED CONDIMENT DISPENSER SET AND RACK THEREFOR

Edward M. Grandinetti, 6606 10th Ave.,
Los Angeles, Calif.

Filed July 28, 1960, Ser. No. 61,557

Term of patent 7 years

(Cl. D44—22)

FIG. 1.

FIG. 3.

FIG. 1 is a front elevational view of a combined condiment dispenser set and rack therefor showing my new design, with one dispenser in detached condition;

FIG. 2 is a side elevational view; and

FIG. 3 is an elevational view taken substantially in the direction of line 3—3 of FIG. 2, with one dispenser in detached condition.

I claim:

The ornamental design for a combined condiment dispenser set and rack therefor, substantially as shown.
